UNITED STATES PATENT OFFICE

2,007,454

AMPOULE

Harold N. May, Chicago, Ill.

Application August 19, 1933, Serial No. 685,851

1 Claim. (Cl. 128—218)

The present invention relates to a container and a closure therefor and has particularly to do with an ampoule or similar article.

Originally, hypodermic injections were prepared in bulk. It was usual and customary for a dentist, physician, or veterinarian to maintain a case containing bottles of medicinal liquids, each liquid comprising a solution of a selected strength of a useful medicament. The liquids were used 10 to fill or partially fill the barrel of a hypodermic syringe. Bulkiness and uncertainty of dosage were disadvantages inherent to this method.

Such hypodermic injections were produced mainly within the confines of a laboratory. It 15 was possible in the laboratory to make sterile solutions of potent material, obtain uniformity therefor, but exact dosage in the hands of the user was impossible. It was irksome to carry a large number of bottles of solutions.

20 The selected liquid was drawn into the barrel of a syringe in measured quantity but this arrangement was difficult of operation and there were variations in the quantity drawn in due to the fit of the plunger within the syringe barrel.

25 Next came hypodermic or hypodermatic tablets. Necessarily, these are made by admixing the potent medicine with a vehicle. The mixture is run through a tabletting machine. Absolute uniformity of mixture of medicament and vehicle 30 appears impossible. It has repeatedly been demonstrated that the percentage of active ingredient in relation to one portion of a mixture varies radically with the medicinal strength of another portion of the same mixture which went through 35 the same batch mixing device and at the same time.

Lack of uniformity was not the only difficulty. Distilled water was not always convenient for use 40 as a solvent. Often polluted or impure water was utilized, perhaps with disastrous results. An ability to obtain the precise amount of water best suited for the purpose was not present and frequently the physician, dentist, or veterinarian 45 was called upon to mix the tablet in water held in the bowl of a tablespoon or in some other crude vessel. Uniform solution was impossible.

When the physician, dentist, or veterinarian attempted to draw a dissolved charge of potent material into a syringe, his success varied. The 50 result was that the dose given by a hypodermic injection and made from a tablet, even under the best of circumstances, was uncertain.

The latest step has been to provide ampoules 55 containing the selected quantity of medicament in solution, that is, in a single ampoule enough

of a solution to equal a dose, say for example, one eighth of one grain of cocaine hydrochloride. Glass vials or cylinders are used. One end of the vial or cylinder is provided with a movable plug and the other end with a puncturable head. The hypodermic needle is used to puncture the head coincidentally with the disposition of the ampoule in the barrel of a syringe. Thus greater accuracy was obtained than is possible by either of the previously described methods of preparing 10 hypodermic injections.

5 The present invention is an improvement over previously employed ampoules. It is intended for use in a syringe having a needle disposed to puncture the head of the ampoule and a plunger to 15 force, longitudinally of the ampoule, a plug disposed adjacent the other end of the glass vial or cylinder.

The objects of the present invention are the provision of new and novel ampoules; an improved puncturable closure therefor; and a better, more positive, air-tight and sanitary means 20 for capping with puncturable material the end of a glass vial or the like.

These objects, and such other objects as may 25 hereinafter appear, are obtained by the novel construction, unique arrangement, and improved combination of the several elements which constitute the single form of the invention illustrated in the accompanying drawing, hereby made 30 a part of this specification, and in which:

Figure 1 is a longitudinal section through a device embodying the subject matter of the invention;

Figure 2 is a diametric section on the line 2—2 35 of Figure 1; and

Figure 3 is a fragmentary elevation of the end of the ampoule completely assembled for marketing.

Like reference characters are used to designate 40 similar parts in the drawing and in the description of the invention which follows.

The ampoule illustrated is designated 10. It is shaped like a conventional homeopathic vial, and comprises an open ended cylindrical section 11, 45 generally of uniform diameter, terminating in shoulders 12, a neck 13 and a squared or rimmed mouth 14. The diameter of the squared mouth is slightly less than the diameter of the body 11. The open bottom end of the cylinder 11 is closed 50 by a plug 16, which plug is of any suitable compressible material which will not contaminate the contents of the vial.

While closing the end of the ampoule against 55 liquid seepage, the plug should be movable longi-

tudinally of the cylinder for the purpose of discharging any liquid contained therein through the neck 13 and mouth 14, when the head is opened by a puncture therein, as by way of the 5 barrel of a hypodermic needle which is shown in dotted outline in Figure 1.

Such needle has a pointed, hollow, cylindrical section 11 extending through the closure member at the neck end of the ampoule. An enlarged portion 10 on said needle and designated 18 is of soft metal and is used for snugly securing the needle upon the barrel of a hypodermic syringe. Said needle also has an extending cylindrical, pointed section 19 intended to be forced into flesh. The 15 discharge of the ampoule is through an axial passage of generally uniform diameter coextensive with the needle as illustrated.

For closing the neck end of the ampoule, a cap 20 is provided. This may be of a suitable rubber 20 or any other suitable sturdy but flexible material. The cap may be a combination of flexible and rigid material, if preferred. The cap or head comprises an end section 21 in which there is a seat 22, such seat being depressed to provide a guide for centering section 17 of the hypodermic needle. The 25 depressed seat extends inwardly of the mouth of the ampoule. It possesses the tendency of causing the needle, when it is forced through the head, to seek the axis of the ampoule, thus avoiding contact with the walls of glass forming the flaring mouth and neck of the ampoule. This 30 seat may be eliminated if desired.

Depending from the end section 21 is an annular section 23 of relatively thin material coextensive with and adapted to shape itself to conform with the external mouth structure of the ampoule. Immediately adjacent and depending from the annular section 23 is another annular section 24 integral with the remainder of the 35 closure member, the material however being of greater thickness and with either a smooth internal periphery or knurled or tabbed or formed with slits therein as is shown in Figure 2 to provide a plurality of independent gripping surfaces 25 rather than a single gripping surface as where 40 the surface is a continuous annular section. The gripping surface or surfaces closely engage the exterior of the neck of the bottle, the purpose of the knurls or slotted structure being to reduce 45 the tendency of the closure member to slip or be twisted upon the ampoule neck.

The ampoule may be employed as already described, or there may be placed thereabout or 55 thereover a foil band or cap or the ampoule may be dipped into a viscous material which subsequently dries thereover to provide an air tight cover which may be readily sterilized by dipping in the usual sterilizing solutions. A metallic or foil band about the head may be similarly steri-

lized. One form of band 27 is illustrated in Figure 3 and has a flange 28 at its top edge. Across the opening in the top of the band is a thin foil disk 29, readily puncturable by a needle.

The diameter of the cap and covering thereover is substantially the same as the diameter of the cylinder 11, thus making the ampoule a generally cylindrical cartridge adapted to fit into the barrel of a syringe without binding or undue stress at any point.

That there is a uniform strain upon all portions of the ampoule prevents fracture or collapse. Such a structure provides an improved ampoule in that the cap is not readily displaceable therefrom, and will resist a large degree of outward 15 pressure while concurrently supporting or strengthening the wall of the ampoule at the constricted neck and mouth portion thereof. No special machinery is needed for attaching the head.

The close hugging of the rubber cap over the mouth or flange of the ampoule while adapting itself to the indented neck of the ampoule makes the entire unit airproof and sterile. The flared mouth or flange of the ampoule serves as a lock 20 against the smaller neck portion of the rubber caps and in this manner it will resist great 25 pressure.

Further, the rubber ears surrounding all of the ampoule end and having a sufficient thickness of 30 wall and bottom, protects the tube or ampoule against breakage and the resiliency of the bottom protective flange acts as a rebound agency to greatly relieve tension and pressure on the ampoule and at the same time practically eliminates 35 regurgitation.

On the cap 27, a number or other designation may be used for identifying the solution in the ampoule to which the cap is attached.

What is claimed as new and is desired to be secured by Letters Patent of the United States is:

An ampoule comprising a body generally cylindrical in configuration, said body having an elongated neck surrounding the mouth of said ampoule, said neck having a lip of less diameter than 45 said body and of greater diameter than said neck, a one piece slip-over cap of elastic material having an external uniformly cylindrical periphery of slightly less diameter than the diameter of said body, the cap comprising a section of reduced 50 thickness fitting snugly about the lip of the ampoule, an internally longitudinally ribbed section of greater thickness fitting about the neck of said ampoule, and a closed end having a depressed portion at its center extending into the mouth of said ampoule, and an elastic plug adapted to serve as a piston head within and closing the other end of said ampoule.
